ATTORNEYS

UNITED STATES PATENT OFFICE.

PERRY M. CONDON, OF ALBANY, NEW YORK.

TOY.

1,328,719.

Specification of Letters Patent. Patented Jan. 20, 1920.

Application filed May 10, 1919. Serial No. 296,046.

To all whom it may concern:

Be it known that I, PERRY M. CONDON, a citizen of the United States, and a resident of Albany, in the county of Albany and 5 State of New York, have invented certain new and useful Improvements in Toys, of which the following is a specification.

My invention is an improvement in toys, and has for its object to provide a toy in 10 the form of a wheeled vehicle having a seat for an occupant and having means for tossing a ball from the front of the vehicle to the occupant in the seat, and for guiding the ball back to the front of the vehicle, said 15 tossing means being spring controlled and being movable into position to toss the ball by the occupant of the seat.

In the drawings:

Figure 1 is a side view of the improved 20 toy;

Fig. 2 is a top plan view.

In the present embodiment of the invention, the vehicle comprises a body 1 in the form of a plate of suitable size having bolsters 2 at its ends, to which are connected 25 axles having wheels 3 on their ends. A seat 4 is arranged above the body of the vehicle, the said seat being supported by braces 5, and this seat is approximately half the 30 length of the body of the vehicle.

An arm 6 of channel shape is pivoted to the body just in front of the front end of the seat, as indicated at 7, and a coil spring 8 is arranged between this arm and the adjacent brace 5, the spring acting normally 35 to swing the arm upward into the dotted line position of Fig. 1.

The arm is drawn downward by a cord 9 which passes from the free end of the arm 40 through eyes 10 at the front end and on the under face of the body, and thence upwardly through an opening 11 in the body to a connection with the seat, as indicated at 12, in such position that it will be convenient to 45 the grasp of the occupant of the seat.

This arm 6 is, as before stated, channel shaped, having the channel rearwardly, and it is adapted to receive a ball 13, the ball, when the arm is in the full line position of 50 Figs. 1 and 2, resting at the outer end of the arm in the channel. It will be obvious that when the arm is released by releasing the string 9, the spring 8 will throw the arm up into the dotted line position of Fig. 1 and 55 the ball will be tossed to the occupant of the seat. By means of the string the arm may

be returned to set position, that is, to the full line position of Fig. 1, and the ball may be returned to the channel of the arm by means of a trough or chute 14 which leads 60 from the seat to the rear end of the arm 6 when the said arm is in downward or set position. This chute extends through a notch 15 in the side of the seat to a position convenient for the rider to drop the ball 65 therein.

In operation, the occupant of the seat may draw the arm downwardly into the position of Fig. 1, and when the ball is dropped into the chute it will roll to the front end of 70 the arm. When the string is released, it being understood that the arm is held lowered by traction on the string, the arm will be flung upward and the ball will be tossed backward to the occupant of the seat. 75

Referring to the drawing, it will be noticed that the ends of the bolster 2 are provided with screw eyes 20, with which are connected the ends of a cord 21. By means of this cord the child may steer the vehicle 80 or may draw the same.

I claim:

1. A device of the character specified comprising a wheel supported body, a seat at the rear of the body and elevated above the same, an arm hinged to the body at the front of the seat and adapted to swing down upon the body or upward into vertical position against the forward end of the seat, a spring normally pressing the arm upward, 85 said arm being channel shaped and being adapted to receive a ball to be tossed to the occupant of the seat by the upward movement of the arm, means adjacent to the occupant of the seat for drawing the arm down, 90 and a chute leading from the seat to the lower end of the arm and registering with the channel of the arm when the arm is lowered. 95

2. A device of the character specified comprising a wheel supported body, a seat at the rear of the body, an arm hinged to the body at the front of the seat and adapted to swing down upon the body or upward into vertical position against the forward end of the seat, a spring normally pressing the arm upward, 100 said arm being channel shaped and being adapted to receive a ball to be tossed to the occupant of the seat by the upward movement of the arm, and means adjacent to the occupant of the seat for drawing the arm down. 105

110

3. A device of the character specified comprising a wheel supported body, a seat at the rear of the body, an arm hinged to the body at the front of the seat and adapted 5 to swing down upon the body or upward into vertical position against the forward end of the seat, and a spring normally pressing the arm upward, said arm being channel

shaped and being adapted to receive a ball to be tossed to the occupant of the seat by 10 the upward movement of the arm.

PERRY M. CONDON.
